CLAIM

We claim the ornamental design for a stand for a PDP (plasma display panel) TV, as shown and described.

DESCRIPTION

FIG. 1 is a perspective view of the stand for a PDP (plasma display panel) TV showing the new design;

FIG. 2 is a Front Elevation View thereof;

FIG. 3 is a Rear Elevation View thereof;

FIG. 4 is a Left-side Elevation View thereof;

FIG. 5 is a Right-side Elevation View thereof;

FIG. 6 is a Top Plan View thereof;

FIG. 7 is a Bottom Plan View thereof;

FIG. 8 is a Rear Perspective View thereof;

FIG. 9 is a Right-side Elevation View showing this design article in use thereof; and,

FIG. 10 is a Front Elevation View showing this design article in use thereof.

The broken line showing of a plasma display TV is for illustrative purposes only and forms no part of the claimed design.
